US0D1037464S

(12) **United States Design Patent** (10) **Patent No.:** **US D1,037,464 S**
(45) **Date of Patent:** **** Jul. 30, 2024**

(54) **ELECTRODE**

(71) Applicant: **BTL Industries**, Sofia (BG)

(72) Inventor: **Vojtech Kubik**, Prague (CZ)

(73) Assignee: **BTL Industries**, Sofia (BG)

(**) Term: **15 Years**

(21) Appl. No.: **29/844,718**

(22) Filed: **Jun. 30, 2022**

(30) **Foreign Application Priority Data**

May 19, 2022 (EM) 009031669-0004
May 19, 2022 (EM) 009031669-0005

(57)

CLAIM

The ornamental design for an electrode, as shown and described.

DESCRIPTION

FIG. 1 is a top front isometric view of an electrode showing the claimed design;

FIG. 2 is a bottom rear isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

1 Claim, 4 Drawing Sheets
